UNITED STATES PATENT OFFICE.

PATRICK H. MACK AND FREDERICK H. MACK, OF BRADFORD, PENNSYLVANIA,
ASSIGNORS TO OIL WELL SUPPLY COMPANY, OF PITTSBURGH, PENNSYLVANIA, A CORPORATION OF PENNSYLVANIA.

WELL-PACKER.

1,145,155.

Specification of Letters Patent. Patented July 6, 1915.

Application filed November 16, 1914. Serial No. 872,379.

To all whom it may concern:

Be it known that we, PATRICK H. MACK and FREDERICK H. MACK, both citizens of the United States, residing at Bradford, in the county of McKean and State of Pennsylvania, have invented certain new and useful Improvements in Well-Packers; and we do hereby declare the following to be a full, clear, and exact description of the invention, such as will enable others skilled in the art to which it appertains to make and use the same.

Our invention relates to that class of devices commonly termed well-packers, which are used in connection with the casing and tubing of Artesian wells, oil wells, or like deep wells, for shutting off the water from the oil bearing sands or from the lower levels of the well. Such packers, as commonly employed, are of two classes, viz., those known in the art as anchor packers wherein tubing extends from beneath the packer proper down to the bottom of the well as a support for the packer proper and as a means of causing the packing to engage the walls of the well; and those known in the art as wall packers wherein means are provided for automatically engaging the walls of the well and thus supporting the packer proper directly from the walls of the well. The first named, or anchor packers, are commonly and preferably employed where it is desirable to apply the packer to the tubing near the bottom of the well, and but a short extension of the tubing or a short "anchor" is required, while the last named are deemed preferable where the packer is to be applied to the casing or tubing some distance above the bottom of the well. In both classes of well packers, however, the packing ordinarily used is a hollow cylinder or annulus of rubber or equivalent compressible and expansible material, in combination with a packer body comprised of telescoping sections of tubing whereby the weight of the superposed casing or tubing is utilized to compress the rubber annulus, and by reason of the lateral expansion thereof effect the packing of the well. An existing trouble with this class of packers experienced in casing wells is the entry of the gas into the annular packing between the packing and the body member of the packing or the tubing which it sur-

rounds, as a result of which it frequently 55 happens that the rubber annulus is so expanded by the gas that it is at times stripped from the tubing by friction against the well walls while attempting to lower the packing to position in the well, and at other 60 times where the pressure of the gas is great is ruptured and rendered inefficient after the packing of the well has been effected.

The object of our invention is the prevention of the entrance of gas to the interior 65 of the packing or between the compressible and expansible packing member and the tubing or body member, whereby the premature expansion as well as any subsequent 70 rupture of the packing annulus is prevented.

To this end our invention generally stated involves the application of the weight of the superposed tubing to a packing member in such manner as to cause said packing member to engage the tube or body member of 75 the packer and thus prevent the entrance of gas between said body member and the annular compressible packing member proper.

It also involves the utilization of the weight of the superposed tubing not only 80 to compress the annular compressible and expansible packing member proper which engages the walls of the well, but also a supplemental packing member which engages the tubing or body member of the packer. 85

There are other, further features of invention involving particular combinations of elements, as well as particular features of elemental construction whereby the purposes of our invention are effected. 90

In the drawings chosen for the purpose of illustrating our invention, the scope whereof is pointed out in the claims, Figure 1 is a longitudinal central sectional view of our invention as applied to a wall packer, 95 showing the relative positions the parts occupy before and when the packer is about to be lowered into a well. Fig. 2 is a view similar to Fig. 1, but showing the relative position of the parts when the packing of the 100 well has been effected. Fig. 3 is a longitudinal central sectional view of our invention as applied to an anchor packer, showing the relative positions the parts occupy before, and when the packer is about to be lowered 105 into a well, and Fig. 4 is a view of the anchor packer shown in Fig. 3, the parts being in the relative positions they occupy

when the packing of the well has been effected.

Like symbols refer to like parts wherever they occur.

5 We will now proceed to describe our invention more fully so that others skilled in the art to which it appertains may apply the same.

10 In the drawings, 1 indicates a coupling collar whereby the packer is connected or coupled to a string of tubing. This collar is threaded internally as at 1^a for connection with the pumping tube above the packer and at 1^b for connection with the body member 2 of the packer. The collar 1 may also be roughened or threaded as at 1^c to facilitate the grabbing of the packer by a fishing tool, if the same becomes necessary. The under surface of the collar 1 is preferably 15 recessed as at 1^d to receive the upper end of an annulus of compressible and expandable material constituting the packing proper.

20 Surrounding the body member 2 of the packer is a hollow cylinder or annulus 3 of 25 a compressible and expandable material, preferably rubber, which constitutes the packing proper, the function of which when compressed is to expand diametrically and engage the walls of the well.

25 Loosely encircling the body member 2 of the packer just below and in contact with the compressible and expandable hollow cylinder or annulus 3 is a sliding ring 4, preferably formed on its upper surface similar to the 30 under surface of collar 1, that is to say with a countersunk or recess 4^a for the reception of the reduced lower end of packing member 3. The under surface of loose or sliding ring 4 is also recessed as at 4^b for the 35 reception of a supplemental packing, and the walls of said recess 4^b are preferably inclined downward and outward from body member 2 of the packer.

40 On the body member 2 below the sliding ring 4 is a second loose ring 5 which telescopes with the first named loose or sliding ring 4, and the upper surface of the ring 4 is recessed as at 5^a, the walls of said recess inclined upwardly and outwardly from the 45 body member 2 of the packer.

45 Interposed between the two telescoping rings 4 and 5 is a supplemental packing member 6 which like packing member 2 is also formed of some compressible material, 50 preferably rubber, though lead or a like substance may be utilized in this position if preferred.

55 It is specified herein, though not for purposes of limitation thereto, that the walls of recesses 4^b and 5^a are inclined relatively to the body member 2 of the packer, as the function of the rings 4 and 5 is to force the supplemental packing 6 against the body member 2 of the packer, and inclined walls 60 are best adapted to effect that purpose, and

further because the effective pressure on the packing can be controlled by the inclination given to the walls of the recess.

65 The cross section of annular packing 6 will preferably correspond to the cross section of the cavity formed by the recesses 4^b, 5^a, though a packing of any other suitable cross section may be employed, as for instance, a circular or oval cross section.

70 The body member 2 of the packing it will be noted extends loosely through the packing member 3, the ring 4, the supplemental packing 6 and the ring 5, so that said members may slide longitudinally of the body member 2, and terminates in a peripheral shoulder 2^a which prevents the escape of the parts mentioned while it permits the free downward movement therethrough of body member 2 of the packer. As a consequence of this construction the superposed 75 weight of the tubing above collar 1 will, when the lower ring 5 is fixed or adequately supported, first compress the packing member 3 and force it in contact with the walls of the well, and acting through packing 3 80 will force ring 4 down on supplemental packing 6 compressing the same and causing it to tightly engage the periphery of body member 2 so that no gas can enter between the supplemental packing 6 and the 85 body member 2 of the packer, and consequently gas is prevented from entering between the body member 2 of the packer and the packing member 3 of the packer.

90 Up to this point the description and illustration of our devices apply equally to the wall packer shown in Figs. 1 and 2 of the drawing, and the anchor packer shown in Figs. 3 and 4 of the drawing being identical in both constructions. Thereafter the invention involves only the selection of the means for anchoring the ring member 5 at the desired point in the well, and for this purpose any known and effective means now applicable to anchor packers or wall packers 95 may be selected according to the preference of the constructor or the position the packer is to occupy in the well.

100 In Figs. 3 and 4 of the drawings the ring member 5 is threaded as at 5^b for the attachment of a sleeve member 7 of sufficient length to permit of the necessary downward movement of body member 2 through ring member 5 to compress the packing members 3 and 6, and to the lower end of said sleeve 105 member 7 is applied a coupling 8 for connecting the required anchor string of tubing to the packer. In Figs. 1 and 2 of the drawing, the lower end of ring 5 is tapered as at 5^c or takes the form of a truncated hollow 110 cone, for coaction with the slips 9 of a wall anchor, which may be of any preferred construction.

115 In the present instance we have chosen for purposes of illustration, but not for lim- 120

itation, the wall-anchor shown and described in connection with the oil well packer of Mack Patent, No. 1,009,327 of November 21, 1911, wherein the slips 9 have a loose or pivotal connection with slip cage 10, and are collapsed by the action of friction springs 11—the anchor being of that particular class known in the art as a wall anchor—and for a further description thereof, if desired, reference is herein made to said prior Patent No. 1,009,327 of November 21, 1911.

The construction of our devices being substantially such as hereinbefore pointed out, their application and operation will be as follows: Provision having been made to support the packing 3 at the desired point in the well, either by the attachment of a wall anchor of the character indicated in Figs. 1 and 2 of the drawings, or by attaching there- 20 to a bottom anchor of tubing as provided for in Figs. 3 and 4 of the drawing, the devices, the elements thereof occupying the relative positions indicated in Figs. 1 and 3 of the drawings, are lowered into the well, 25 the weight of the packer and all below the same being suspended from the superposed tubing by the collar, at the lower end of body member 2 of the packer. Having been lowered to the desired point in the well, in 30 case of a bottom anchor packing, the arrest of the downward movement of the anchor and its contact with the bottom of the well will afford the required support for the ring member 5, and in case of the "wall-anchor" 35 the superposed tubing by means of which the packer is lowered will be manipulated to set the wall-anchor and support ring member 5 from the walls of the well and thus afford the ring member 5 and packing the 40 required support at the desired point in the well. A support for ring member 5 having thus been secured, the weight of the superposed tubing is allowed to descend on packing member 3, and as body member 2 is 45 movable through packing member 3, ring members 4 and 5 and supplemental packing 6, the packing 3 will, by the telescoping of the parts, be pressed outward against the walls of the well and the supplemental packing 50 6 will be pressed inward against body member 2 of the packing thus preventing gas from following the outer surface of body member 2 to a point inside of packing member 3, which will effectually prevent the 55 stripping or rupture of the packing member by gas pressure.

It is to be noted that while in the assembling of the elements 1, 2, 3, 4, 5, 6, the screw connections between coupling member 60 1 and body member 2 may and preferably should be utilized to put a moderate initial compression on supplemental packing 6, yet the effective operation of the packing is not dependent on any screw connection between the elements but is effected by weight

and pressure of the superposed tubing acting through the telescoping or relatively movable coacting members constituting the packing, and insures an effective application of the supplemental packing which can not 70 be obtained where a screw follower or gland construction is adopted.

Having thus described our invention, what we claim and desire to secure by Letters Patent is:

1. In a well packer, the combination of a packer having a body member, a supplemental compressible packing member, a support for the packing member, said body member of the packer and the support for 80 the packing member being relatively movable longitudinally of the packer, and means for transferring the weight superposed on the packer to said packing member, said means being adapted to compress the packing member against the body member of the packer.

2. In a well packer, the combination of a packer having a body member, a packing member for engaging the walls of a well, a 90 supplemental packing member adapted to engage the body member, a support for the supplemental packing member, the support and the body member of the packer being relatively movable longitudinally of the 95 packer, and means for transferring pressure from the first named packing member to the supplemental packing member, said means being adapted to compress the last named packing member against the body member 100 of the packer.

3. In a well packer, the combination of a packer having a body member, a supplemental compressible packing member, a support for the compressible packing member, 105 the body member of the packer and the support being relatively movable longitudinally of the packer, means for transferring the weight superposed on the packer to the compressible packing member, said weight-transferring means and body member of the packer being also relatively movable longitudinally of the packer, said support and said weight-transferring means being adapted to compress the supplemental packing 110 member against the body member of the packer.

4. In a well packer, the combination of a body member, a packing member, a plurality of ring members, means whereby the weight 120 of superposed tubing may be transmitted to the packer, a supplemental packing member interposed between the ring members, one of said ring members being interposed between the two packing members, and means for supporting one of the ring members in the well, said ring and packing members being movable with relation to each other and to the body member of the packer whereby any load imposed on the well packer causes the 125

4
supplemental packing member to engage the body member of the packer.

5. In a well packer, the combination of a body member, a packing member, a plurality of telescoping ring members on the body member below the packing member, a supplemental packing member interposed between the telescoping ring members, and means for supporting in a well the lower of 10 said telescoping ring members.

6. In a well packer, the combination of a packer having a body member, a supplemental compressible packer, a support for the packing member, means for transferring 15 the weight superposed on the packer to the compressible packing, the body member the

support and the weight-transferring means being relatively movable longitudinally of the packer and said support and said weight-transferring means being adapted to telescope and to compress the included packing member against the body member of the packer. 20

In testimony whereof we affix our signatures, in the presence of two subscribing witnesses. 25
